UNITED STATES PATENT OFFICE.

HORACE B. McCABE, OF CHICAGO, ILLINOIS; ASSIGNEE TO GISHOLT MACHINE COMPANY, OF MADISON, WISCONSIN, A CORPORATION OF WISCONSIN.

ATTACHMENT FOR REGULATING TIME-RECORDING REGISTERS.

1,104,125.

Specification of Letters Patent.

Patented July 21, 1914.

Application filed March 6, 1913. Serial No. 752,266.

To all whom it may concern:

Be it known that I, HORACE B. McCABE, a citizen of the United States, residing at Chicago, in the county of Cook and State 5 of Illinois, have invented certain new and useful Improvements in Attachments for Regulating Time-Recording Registers, of which the following is a specification.

My invention relates to attachments for regulating time recording registers, and is in the nature of an improvement on other devices heretofore invented and patented by me, and particularly the time recording registers forming the subjects-matter of my 15 Letters Patent of the United States #946,858, dated January 18, 1910, and of my application for United States Letters Patent filed November 8, 1911, Serial No. 659,125.

20 The primary object of my invention is the provision of an improved attachment for regulating time recording registers which shall have means for arresting during a given time the periodic change of the recording type of the register.

With the above and other objects in view, this invention consists substantially in the construction, combination, and arrangement of parts, all as hereinafter described, shown 30 in the accompanying drawings which form a part of this specification and illustrate the preferred embodiment of my invention, and more specifically set forth in the subjoined claims.

35 In the drawings, Figure 1 is a side elevation of my invention showing it attached to a time recording register, and showing in outline in dotted lines an irregularly shaped frame plate; Fig. 2 is an end elevation of

40 my invention showing it attached to a time recording register and showing a portion of the register in rear elevation; Fig. 3 is a side elevation of my invention showing a different position of the parts from that 45 illustrated in Fig. 1, and including in end elevation a portion of the time recording register; Fig. 4 is an elevation of the opposite end of the recording register shown in Fig. 1; Fig. 5 is a detail view of a portion 50 of my invention shown in Figs. 1, 2 and 3; Fig. 6 is a detail view of an escapement forming part of my invention, and shown in Figs. 1, 2 and 3; Fig. 7 is a side elevation of a modification of my invention showing 55 it attached to a time recording register, and

showing in dotted lines an irregularly shaped frame plate; Fig. 8 is a top plan view of a portion of Fig. 7.

In my former patent and application herein referred to, provision was made for preventing the operation of the recording type of my registers during the interval of time consumed by a workman in stamping the time of stopping a job on one card, and stamping his starting time for another job 60 on a new card. My present invention affords other and improved means for arresting the operation of the recording type.

In the time recording registers heretofore patented and invented by me, and hereinabove referred to, the recording type of the register was locked against operation when the operating handle of the register was at one end of its path of motion, and was free to operate when the operating handle was at 70 the other end of its path of motion. In the use of my present invention, I provide that the recording type of the register may be free to operate, regardless of the position of rest of the operating handle of the register, 75 unless, by the will of the operator, this new attachment for regulating time recording registers be placed in operation. In my recording registers, I shift the recording type by the action of a gravity pawl upon ratchet 80 wheels operatively connected to the recording type. In my present invention, I provide means whereby the gravity pawl, while free to engage in its backward or dragging stroke, is caught in that position and retained from performing its forward operating thrust until by the action of my present invention it is released.

Reference numeral 10 in the drawings indicates the main frame of a time recording 95 register.

11 is the inner frame plate and 12 is the outer frame plate of my improved regulating attachment. These plates are secured to one end of the frame 10 of the time recording register by any suitable means, such as cap screws 13, and are held sufficiently spaced from each other to contain operating mechanism to be later described, the spacing being accomplished also by any suitable 100 means, such as collars 14, upon the cap screws 13. The operating handle of the time recording register is indicated by reference numeral 15, and at each swing of this handle an approximately horizontal shaft 110

16, which forms one of the operating members of the time recording register, is reciprocally oscillated. Rigidly secured to the outwardly extended end of the shaft 16 5 is a presser finger 17. Pivoted upon a journal 18 carried between the frame plates 11 and 12, is an oscillating segment 19, toothed as at 20, and bearing a stud 21 provided with a collar 22. The stud 21 is preferably 10 disposed adjacent the pivoting journal 18 and receives the action of the presser finger 17 at each throw of the handle 15. A tension spring 23, secured at one of its ends in fixed relation to the frame plates 11 and 12, 15 is attached to a stud 24 upon the toothed segment 19 and acts normally to hold the segment in the elevated position illustrated in Fig. 1. In this position the collared stud 21 is preferably in contact with the presser 20 finger 17. When the handle 15 is thrown in either direction, the presser finger 17 moves downwardly, carrying before it the collared stud 21 and lowering the toothed segment 19 to the position illustrated in Fig. 3. A 25 branched rocker arm 25, forming part of the mechanism of the time recording register, in conjunction with other parts, governs the operation of the gravity pawl 26. This gravity pawl 26, by its action, controls the 30 changing of the recording type of the register. Consequently, by control of the rocker arm the action of the gravity pawl 26 may be governed. In the present embodiment of my invention, I provide an extension 27 upon the forward face of the branched rocker arm 25 and place a protruding stud 28 upon the extension 27. Pivoted, as at 29, and operatively disposed 35 with relation to the stud 28, is a trigger 30, having a shoulder 31 adapted to engage the stud 28. A spring member 49, fixed at one 40 end in relation preferably to the frame plate 11, bears at its free end against a stud 50 borne upon the trigger 30 and holds the trigger normally in a position to engage the stud 28 when the stud is oscillated downwardly. Let it be noted that the backward draw and forward driving thrust of the 45 gravity pawl 26 is controlled through the reciprocal oscillation of the branched rocker arm 25. At the time of the backward draw of the gravity pawl 26, the stud 28 oscillates with the rocker arm 25 to a point adjacent the shoulder 31 of the trigger 50 55 30, and the shoulder 31 will engage the stud 28 and hold the gravity pawl in its backwardly drawn position, arresting its forward thrust. An extension 32 upon the toothed segment 19 engages an angled arm 60 65 33 upon the trigger 30, and normally holds the trigger out of operative relation to the stud 28 when the segment is in the position illustrated in Fig. 1. However, when the segment 19 has assumed the position shown in Fig. 3, the extension 32 is withdrawn

from the angled arm 33 and the trigger is left free for engagement with the stud 28.

At each throw of the operating handle 15 of the time recording register, the presser finger, acting upon the stud 21, throws the toothed segment 19 downwardly into the position illustrated in Fig. 3, leaving the gravity pawl 26, if it has been actuated, in its backward drawn position and locked in that position by engagement of the trigger 30 with the stud 28. The driving thrust of the gravity pawl 26 is therefore delayed until the return of the toothed segment 19 into its upward position and until the extension 32 has moved the angled arm 33 sufficiently 70 to release the stud 28 from engagement with the trigger 30. This downward throw of the toothed segment 19 is, of course, performed against the pull of the tension spring 23, the spring having a normal tendency to draw 75 the toothed segment back into the upper position shown in Fig. 1. The action of the spring 23, however, is retarded by an escapement mechanism.

Mounted upon a shaft 34 journaled for 90 oscillation in the frame plates 11 and 12, is a vibrator 35, preferably weighted at its ends by weights 36 and 37, and slotted at 35^a for the passage of a journal to be hereafter described. This vibrator carries two escapement pins 38 and 39. A journal 40 is mounted in the frame plates 11 and 12 and passes through the slot 35^a of the vibrator 35. Rotatably mounted upon the journal is an escapement wheel 41, co-operating with the pins 38 and 39 to oscillate the vibrator 35. A stud 42 protrudes from the side of the escapement wheel 41, preferably adjacent the periphery of the wheel, and a friction pawl 43 is eccentrically 100 mounted for oscillation upon the stud 42. Central upon the journal 40 is a circular friction disk 44 having a groove 45 co-operating with the pawl 43 to lock the escapement wheel 41 and the disk 44 into fixed 105 relation when the disk is actuated in one direction, but allowing free oscillation of the disk in the opposite direction. A pinion 46 central upon the shaft 40 is fixed to the disk 44 and has its teeth in engagement with the teeth 20 of the segment 19. When the segment 19 is thrown downward, the pinion 46 drives the disk 44 about the journal 40, the friction pawl 43 being so mounted as to allow this rotation of the 110 disk 44. When, however, the presser finger 17 recedes, at the end of the throw of the operating handle 15, from its contact with the stud 21, the action of the tension spring 23 moves the segment upwardly. The pull 115 of the spring 23 is conveyed through the teeth 20 of the segment 19 and through the pinion 46 to the disk 44, and, by reason of the frictional contact between the pawl 43 and the disk 44, the pawl, which rides 120 125 130

in the groove of the disk, binds against the disk and locks it and the escapement wheel 41 into fixed relation. The upward pull of the spring 23, therefore, is conveyed to the 5 escapement wheel 41 and causes it in co-operation with the escapement pins 38 and 39 to actuate the vibrator 35. This action of the vibrator 35 retards the upward movement of the toothed segment 19 in practice 10 about fifteen seconds, though this period of time may be varied as desired by the construction of the escapement. To insure proper frictional contact at all times between the pawl 43 and the disk 44, I secure 15 a spring 47 upon the escapement wheel 41 and cause one of its ends to bear upon the friction pawl 43 and hold it normally in contact with the groove 45 of the disk 44. A stud 48 protrudes inwardly, preferably 20 from the frame plate 12, and is disposed in the path of the toothed segment 19 to operate as a stop to the upward oscillation of the segment.

In the mechanism just described, when the 25 gravity pawl 26 is actuated, the trigger 30 engages the stud 28 and holds the gravity pawl 26 in its backwardly drawn position at each swing of the operating handle 15 of the time recording register, but, in case 30 it is desired to operate the register without any retarding action, I provide means for throwing the trigger 30 into such a position that it will not engage the stud 28. This means comprises an eccentric cam 51 mounted 35 upon a shaft 52 which protrudes from the frame plate 11, and an extension 53 upon the trigger 30 coöperating with the cam to throw the trigger out of the path of the stud 28. An extension 54 protrudes from 40 the side of the eccentric cam 51 and extends beyond the outer face of the frame plate 12. This extension 54 bears an indicator arm 55 and a preferably square hole 56 is sunk in its outer end for the insertion 45 of a key.

The words "Off" and "On" are placed upon the outer surface of the frame plate 11, for convenience in indicating to the operator the position of the cam 51 with respect to the trigger extension 53. When it 50 is desired to throw the trigger out of the path of the stud 28, the operator inserts his key into the key socket 56 and turns the eccentric cam 51 in a clockwise direction. 55 Studs 57 and 58 protrude from the outer surface of the frame plate 12 and lie in the path of the indicator arm 55, acting as stops for the movement of the indicator arm and the eccentric cam 51.

60 The primary object of my invention may, of course, be accomplished by mechanisms differing in construction from that heretofore described. In Fig. 7 is shown such a modification, in which the collared stud 21 65 protrudes from the side of a driving arm

59, upon which the spring member 23 acts in a manner similar to that described in the mechanism shown in Figs. 1, 2, 3, 5 and 6. The arm 59 is pivoted upon the journal 18, and the stud 21 is actuated by the presser finger 17 in the manner heretofore described. In my time recording registers, a gravity operated locking pawl 60 is pivoted for oscillation upon the frame 10, as at 61, and is weighted at its outer end 62. This locking 70 pawl 60 coöperates with a ratchet wheel 63, to prevent retrograde movement of the recording type of the register, but if, when it is in locking coöperation with the ratchet wheel 63, it is rigidly held in such position, 75 it may be employed as a detent and will arrest the change of the recording type of the register until it be released for oscillation upon its pivot. To accomplish this rigid holding of the locking pawl 60, I provide 80 protruding therefrom a stud 64, and for co-operation with the stud I provide a trigger 65 pivoted on a pin 66 and provided with a shoulder 67 for engagement with the stud 64. A spring member 68 fixed at one end in 85 relation to the pin 66 bears at its free end against a stud 69 upon the trigger 65, and tends to draw the trigger against the stud 64. An extension 70 upon the pivoted arm 59 bears a lateral stud 71, which coöperates 90 with an extension 72 of the trigger 65 to maintain the trigger out of operative contact with the stud 64 when the arm 59 is in the position shown in full lines in Fig. 7. When, however, the operating handle 15 of 95 the recording register is actuated, and the presser finger 17 by its action upon the stud 21 has thrown the pivoted arm 59 into the position shown in dotted lines in Fig. 7, no operative contact is had between the stud 71 and the extension 72 of the trigger, which 100 leaves the spring member 68 free to perform its action of drawing the trigger into operative contact with the stud 64. Until the stud 71 again contacts with the extension 72 of 105 the trigger, the locking pawl 62 is rigidly held in its locking engagement with the ratchet wheel 63 and arrests the change of the recording type of the register. As was stated above, the spring member 23 acts 110 normally to draw the pivoted arm 59 upwardly from the position shown in dotted lines in Fig. 7 to the position shown in full lines. For the purpose of delaying this upward oscillation of the arm 59, I provide a 115 piston casing 73 having a small air vent 74 in its closed upper extremity, and provided with a reciprocating piston 75. The piston 75 is connected by a link 76 to the free end of the arm 59, and is also valved to admit of 120 its ready downward movement but in such manner that the valve is closed during upward movement. Preferably, I construct my valve by centrally boring the piston, as at 77, and enlarging the bore 77 into a ground 125 130

seat 78 for engagement with a ball 79. By the use of this piston, the upward oscillation of the arm 59 is retarded for the length of time which it takes for the air imprisoned by the valve action of the piston to pass from the piston casing 73. A closure 73^a upon the upper extremity of the piston casing 73 forms a stop for the upward oscillation of the piston 75 and the arm 59. A band or stirrup 80, shown in Fig. 8, is secured to the frame plate 11 and serves to hold the piston casing in its proper position.

Fig. 4 is an elevation of the end of the time recording register opposite the end to which my improved attachment for regulating is secured. In the registers forming the subject matter of my Letters Patent of the United States dated January 18, 1910, and my application for Letters Patent filed November 8, 1911, Serial No. 659,125, I provided a cam (designated in that application by reference numeral 139), to which the operating handle of the register was attached, for coöperating with other parts of the mechanism therein described to lock the recording type against change at the time when the operating handle was at one end of its swing. When the operating handle was at the opposite end of its swing, a portion of the surface of the cam at one end was beveled off to release the locking mechanism. In Fig. 4 of my present invention, this cam is indicated by reference numeral 81, and the end portion which was beveled away is indicated by reference numeral 82. Fig. 4 is inserted in this application for the purpose of showing that in the operation of my time recording registers above mentioned in coöperation with my present invention, I bevel away, as at 83, the opposite end of this cam 81, in order that the mechanism coöperating with the cam 81 may at the end of each swing of the operating lever 15 be released from its locking action upon the recording type of the register.

In the drawings forming a part of this specification are shown many parts of my time recording registers which are not here described in detail, for the reason that they form the subject matter of my Letters Patent of the United States No. 946,858, dated January 18, 1910, and my application for United States Letters Patent filed November 8, 1911, Serial No. 659,125.

In the time recording registers heretofore patented and invented by me and hereinabove referred to, the changing of the recording type of the register was accomplished by the periodic actuation of an electric engine, designated in Figs. 1, 3, 4 and 7 of this present application by reference numeral 84. The action of the electrical engine 84 was conveyed through various mechanical parts to the gravity pawl 26, which was drawn backward by the engine

and which, when the engine was deenergized, was given its forward or driving impulse by a spring member. It will be seen that in the application of my invention, and in the use of either of the modifications thereof herein described, this electrically actuated backward pull of the gravity pawl 26 is in no way interfered with. The actuation of the electrical engine 84 in practice occurs generally at periods six minutes, or one-tenth of an hour, apart, and is sustained during a few seconds, normally one or two. Should a workman insert his card in the time recording register and, by swinging the operating handle 15, take an impression on the card just before the actuation of the electrical engine 84, the gravity pawl 26 will perform its backward pull or draw when the engine is actuated, but may, by the action of my present invention, be restrained from accomplishing its forward driving thrust for a period of time of sufficient length to allow the workman to print a new card after printing his old card, before any change is made in the recording type of the register. The exact period of time in which the gravity pawl 26 is restrained from its forward driving thrust may be either longer than, shorter than, or the same as, the period of energizing of the engine; the relation between the two periods being generally immaterial if the workman is afforded sufficient time in which to print two cards. When the action of my present invention is complete, however, the mechanism of the recording register will be released to allow the change of the recording type.

In the present embodiment of the invention the gravity pawl 26 is shown in Figs. 1, 2, 7 and 8 at the end of its thrusting or driving stroke, while in Fig. 3 it is shown at the opposite end of its path of movement or at the end of its drag stroke and in position to perform its thrust. The indicating and printing wheels of the register (shown most clearly in Fig. 2) are designated by reference numerals 86, 87, 88 and 89. They are mounted for rotation upon co-axial shafts, and upon the opposite ends of the respective shafts are ratchet wheels 63, 91, 92 and 93. One end of the gravity pawl 26 contacts with the ratchet points of the wheels 63, 91, 92 and 93, to rotate them step by step, which rotation accomplishes the simultaneous rotation of the number wheels 86 to 89 inclusive. The indicating and printing wheel 86 is mounted upon the same shaft as the ratchet wheel 63, and the pawl 26 drives the ratchet wheel 63 and the wheel 86 once at each stroke of the pawl. During nine strokes of the pawl it is prevented, by means of a side disk 94 secured to the ratchet wheel 63, from contacting with the ratchet wheel 91, but at the tenth stroke of the pawl a notch in the side disk 94 allows the edge of

the pawl 26 to drop sufficiently to engage the teeth of the ratchet wheel 91 which will cause a movement of both wheels 86 and 87. A side disk 95 secured to the ratchet wheel 91 with- 5 holds the pawl 26 from engagement with the ratchet wheel 92 during nine steps of the ratchet wheel 91, but at the tenth step or partial turn of the ratchet wheel 91 a notch in the side disk 95 allows the gravity pawl 10 26 to drop sufficiently to engage the ratchet wheel 92 which causes it to move wheels 86, 87 and 88. One of the notches in the ratchet wheel 92 is cut deeper than the others in order that at every tenth movement of the 15 ratchet wheel 92 the pawl 26 may drop sufficiently to engage the ratchet wheel 93 which will cause movement of all four of the indicating and printing wheels. The edge of the gravity pawl 26 is broken for the pur- 20 pose of causing it to engage properly with the ratchet wheel and side disk described. During the backward stroke of the pawl it rises upon one point of the ratchet wheel 63 and drops into the notch beyond it, and 25 during the forward or thrust stroke the pawl engages the tooth of the ratchet and turns the wheel. The same action of the pawl is had with relation to each of the ratchet wheels in turn as the side disks permit the 30 drop of the pawl to engage the various ratchets. Motion is communicated to the pawl 26 from the electrical engine 84, the communicating means being a lever 96 se- 35 cured to the armature plate 97 of the elec- trical engine 84 and a link 98 joining the free end of the lever to the branched rocker- arm 25. The gravity pawl 26 is pivoted at one of its ends to the rocker-arm 25. A spring 99 is connected to the lever 96 to 40 draw it normally into the position shown in Figs. 1, 2, 7 and 8, while the electrical engine at each actuation operates to draw the lever 96 into the position shown in Fig. 3.

In the accompanying drawings and in the 45 foregoing description are set forth the preferred embodiment of my invention, but it is obvious that one skilled in the art may make modifications of the same without departing from the principle of the invention.

50 What I claim is:

1. The combination with a time recording register, of apparatus for arresting the change of the recording mechanism during a time sufficient to take a plurality of records therefrom.

2. The combination with a time recording register having recording mechanism which is changed by power electrically stored and mechanically expended, of apparatus for ar- 60 resting the expending of the stored power during a time sufficient to take a plurality of records therefrom.

3. The combination with a time recording register, of apparatus for arresting the 65 change of the recording mechanism for a

given time, and a device for rendering the arresting apparatus inoperative.

4. The combination with a time recording register, of apparatus for arresting the change of the recording mechanism for a 70 given time, and a manually operable device for rendering the arresting apparatus inop- erative.

5. The combination with a time recording register, of apparatus actuated by a moving 75 part of the register for arresting the change of the recording mechanism during a time sufficient to take a plurality of records there- from.

6. The combination with a time recording 80 register, of apparatus for arresting the change of the recording mechanism during a time sufficient to take a plurality of rec- ords therefrom, comprising a trigger coöper- 85 ating with the changing mechanism to lock it against change, and an arm adapted by its oscillation to control the engagement of the trigger with the changing mechanism.

7. The combination with a time recording 90 register, of apparatus for arresting the change of the recording mechanism for a 95 given time during a time sufficient to take a plurality of records therefrom, comprising a stud upon the changing mechanism, a trig- ger coöperating therewith to lock the chang- 95 ing mechanism against change, and an arm adapted by its oscillation to control the en- gagement of the trigger and stud.

8. The combination with a time recording 100 register, of apparatus for arresting the change of the recording mechanism during a time sufficient to take a plurality of rec- ords therefrom, comprising a stud upon the changing mechanism, a trigger coöperating 105 therewith to lock the changing mechanism against change, an arm adapted by its oscil- lation to control the engagement of the trig- ger and stud, and mechanism for governing the oscillation of the arm.

9. The combination with a time recording 110 register, of apparatus for arresting the change of the recording mechanism during a time sufficient to take a plurality of rec- ords therefrom, comprising a stud upon the changing mechanism, a trigger coöperating 115 therewith to lock the changing mechanism against change, an arm actuated by the reg- 120 ister and adapted by its oscillation to con- trol the engagement of the trigger and stud, and mechanism for governing the oscillation of the arm.

10. The combination with a time recording register, of apparatus for arresting the change of the recording mechanism during a time sufficient to take a plurality of records 125 therefrom, comprising a stud upon the changing mechanism, a trigger coöperating therewith to lock the changing mechanism against operation, an arm for releasing the engagement of the trigger with the stud, and 130

mechanism for retarding the action of the arm.

11. The combination with a time recording register, of apparatus for arresting the change of the recording mechanism during a time sufficient to take a plurality of records therefrom, comprising a trigger coöperating with the changing mechanism to lock it against change, an arm actuated by the register for releasing the trigger from engagement with the changing mechanism, and escapement mechanism for retarding the releasing action of the arm.

12. The combination with a time recording register, of apparatus for arresting the change of the recording mechanism for a given time, comprising a trigger coöperating with the changing mechanism to lock it against change, an oscillating arm, a spring member acting upon the arm to cause it normally to hold the trigger out of locking engagement with the changing mechanism, means upon the register for oscillating the arm against the force of the spring member and out of operative contact with the trigger, and mechanism for retarding the spring actuated return oscillation of the arm.

13. The combination with a time recording register, of apparatus for arresting the change of the recording mechanism for a given time, comprising a trigger coöperating with the changing mechanism to lock it against change, an oscillating arm, a spring member acting upon the arm to cause it normally to hold the trigger out of locking engagement with the changing mechanism, means upon the register for oscillating the arm against the force of the spring member and out of operative contact with the trigger, and escapement mechanism for retarding the return oscillation of the arm.

14. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm.

15. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking

engagement with the changing mechanism, means upon the register for oscillating the arm out of engagement with the trigger, a spring member for returning the arm to engagement with the trigger, and escapement mechanism for retarding the spring actuated return of the arm.

16. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm comprising a vibrator, escapement pins upon the vibrator, an escapement wheel coöperating with the pins, a pinion adapted to drive the escapement wheel, and a toothed segment upon the oscillating arm engaging the pinion.

17. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm comprising a vibrator, escapement pins upon the vibrator, an escapement wheel coöperating with the pins, a pinion adapted to drive the escapement wheel in one direction and to idle in another direction, and a toothed segment upon the oscillating arm engaging the pinion.

18. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm comprising a vibrator, escapement pins upon the vibrator, an escapement wheel coöperating with the pins, a pinion adapted

to drive the escapement wheel in one direction and to idle in the other direction, and a toothed segment upon the oscillating arm engaging the pinion.

5 19. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm comprising a vibrator, escapement pins upon the vibrator, an escapement wheel coöperating with the pins, a friction disk eccentrically pivoted upon the escapement wheel, a circular cam concentric with the escapement wheel rotatable independently thereof and having a friction surface coöperating with the friction disk to lock the cam and escapement wheel in fixed relation when the cam is actuated in one direction and to idle in the other direction, a toothed pinion fixed upon the cam, and a toothed segment upon the oscillating arm engaging the toothed pinion.

20. The combination with a time recording register, of apparatus for arresting the change of the recording mechanism for a given time, comprising a trigger having a normal tendency to engage the changing mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm comprising a vibrator, escapement pins upon the vibrator, an escapement wheel coöperating with the pins, a spring pressed friction disk eccentrically pivoted upon the escapement wheel, a circular cam concentric with the escapement wheel rotatable independently thereof and having a friction surface coöperating with the friction disk to lock the cam and escapement wheel in fixed relation when the cam is actuated in one direction and to idle in the other direction, a pinion fixed upon the cam, and a toothed segment upon the oscillating arm engaging the toothed pinion.

21. The combination with a time recording register, of apparatus for arresting the change of the recording mechanism for a given time, comprising a trigger having a normal tendency to engage the changing

mechanism and lock it against change, an oscillating arm having contact in one position with the trigger to hold it from locking engagement with the changing mechanism, means upon the register for oscillating the arm out of engagement with the trigger, a spring member for returning the arm to engagement with the trigger, and mechanism for retarding the spring actuated return of the arm, comprising a weighted vibrator, escapement pins upon the vibrator, an escapement wheel coöperating with the pins, a pinion adapted to drive the escapement wheel in one direction and to idle in the other direction, and a toothed segment upon the oscillating arm engaging the pinion.

22. The combination with a time recording register, of apparatus for arresting the change of the recording mechanism for a given time, comprising a trigger coöperating with the changing mechanism to lock it against change, an oscillating arm, a spring member acting upon the arm to cause it normally to hold the trigger out of locking engagement with the changing mechanism, means upon the register for oscillating the arm out of operative contact with the trigger, mechanism for retarding the spring actuated return of the arm, and a stop limiting the return oscillation of the arm.

23. The combination with a time recording register, of apparatus for arresting the change of the recording mechanism for a given time, including a trigger having a normal tendency to engage the changing mechanism and lock it against change, and a movable cam acting upon the trigger to withhold it from locking engagement with the changing mechanism.

24. The combination with a time recording register, of apparatus for arresting the change of the recording mechanism for a given time, including a trigger having a normal tendency to engage the changing mechanism and lock it against change, and a manually operable movable cam acting upon the trigger to withhold it from locking engagement with the changing mechanism.

25. The combination with a time recording register, of apparatus for arresting the change of the recording mechanism for a given time, including a supporting frame, a trigger having a normal tendency to engage the changing mechanism and lock it against change, a manually operable cam for withholding the trigger from locking engagement with the changing mechanism, marks upon the frame, and a pointer upon the cam coöperating with the marks to indicate the position of the cam.

26. The combination with a time recording register, of apparatus for arresting the change of the recording mechanism for a given time, including a supporting frame,

a trigger having a normal tendency to engage the changing mechanism and lock it against change, a manually operable cam for withholding the trigger from locking engagement with the changing mechanism, and stops limiting the movement of the cam.

27. The combination with time controlled registering mechanism, of mechanism for producing a record therefrom, and apparatus actuated by said record producing means for 10 arresting the change of said time controlled

registering mechanism during a time sufficient to take a plurality of records.

In testimony whereof I have signed my name to this specification, in the presence 15 of two subscribing witnesses, on this 1st day of March, A. D., 1913.

HORACE B. McCABE.
